(57) CLAIM

The ornamental design for a three dimensional mastopexy implant, as shown and described.

DESCRIPTION

FIG. 1 is a front view of a three dimensional mastopexy implant showing our new design;

FIG. 2 is a top view of the three dimensional mastopexy implant shown in FIG. 1;

FIG. 3 is a side view of the three dimensional mastopexy implant shown in FIG. 1;

FIG. 4 is a bottom view of the three dimensional mastopexy implant shown in FIG. 1;

FIG. 5 is another side view of the three dimensional mastopexy implant shown in FIG. 1;

FIG. 6 is a rear view of the three dimensional mastopexy implant shown in FIG. 1

FIG. 7 is a top, front, side perspective view of the three dimensional mastopexy implant shown in FIG. 1;

FIG. 8 is a front view of another three dimensional mastopexy implant showing our new design;

FIG. 9 is a top view of the three dimensional mastopexy implant shown in FIG. 8;

FIG. 10 is a side view of the three dimensional mastopexy implant shown in FIG. 8;

FIG. 11 is a bottom view of the three dimensional mastopexy implant shown in FIG. 8;

FIG. 12 is another side view of the three dimensional mastopexy implant shown in FIG. 8;

FIG. 13 is a rear view of the three dimensional mastopexy implant shown in FIG. 8;

FIG. 14 is a top, front, side perspective view of the three dimensional mastopexy implant shown in FIG. 8;

FIG. 15 is a front view of another three dimensional mastopexy implant showing our new design;

FIG. 16 is a top view of the three dimensional mastopexy implant shown in FIG. 15;

FIG. 17 is a side view of the three dimensional mastopexy implant shown in FIG. 15;

FIG. 18 is a bottom view of the three dimensional mastopexy implant shown in FIG. 15;

FIG. 19 is another side view of the three dimensional mastopexy implant shown in FIG. 15;

FIG. 20 is a rear view of the three dimensional mastopexy implant shown in FIG. 15;

FIG. 21 is a top, front, side perspective view of the three dimensional mastopexy implant shown in FIG. 15;

FIG. 22 is a front view of another three dimensional mastopexy implant showing our new design;

FIG. 23 is a top view of the three dimensional mastopexy implant shown in FIG. 22;

FIG. 24 is a side view of the three dimensional mastopexy implant shown in FIG. 22;

FIG. 25 is a bottom view of the three dimensional mastopexy implant shown in FIG. 22;

FIG. 26 is another side view of the three dimensional mastopexy implant shown in FIG. 22;

FIG. 27 is a rear view of the three dimensional mastopexy implant shown in FIG. 22; and,

FIG. 28 is a top, front, side perspective view of the three dimensional mastopexy implant shown in FIG. 22.

The broken lines shown in the figures form no part of the claimed design.

UNITED STATES PATENT AND TRADEMARK OFFICE
CERTIFICATE OF CORRECTION

PATENT NO. : D836,778 S
APPLICATION NO. : 29/542048
DATED : December 25, 2018
INVENTOR(S) : Limem et al.

Page 1 of 1

It is certified that error appears in the above-identified patent and that said Letters Patent is hereby corrected as shown below:

On the Title Page

In the DESCRIPTION, page 2, Column 2, cancel the text beginning with "FIG. 8 is a front view of another three dimensional mastopexy implant showing our new design;" and ending with the text "FIG. 28 is a top, front, side perspective view of the three dimensional mastopexy implant shown in FIG. 22." at page 3, Column 1.

Under the DESCRIPTION, "1 Claim, 25 Drawing Sheets" should read --1 Claim, 7 Drawing Sheets--.

In the Drawings

Cancel figures 8-28.

Signed and Sealed this
Second Day of April, 2019

Andrei Iancu
Director of the United States Patent and Trademark Office
